OPEN AIR CAFETERIA

Albert Ross, Oakland, Calif., assignor to Doggie Diner No. 6, Inc., Oakland, Calif., a corporation of California

Filed July 31, 1959, Ser. No. 57,023

Term of patent 14 years

(Cl. D13—1)

Fig. 1.

Fig. 2.

FIG. 1 is a front elevational view of an open air cafeteria showing my new design; and,

FIG. 2 is a side elevation thereof.

The rear, top, and other side of the structure not shown are substantially plain.

I claim:

The ornamental design for an open air cafeteria, as shown and described.
